GIOVANNI EMANUELE ELIA, OF ROME, ITALY.

FIRING APPARATUS FOR SUBMARINE MINES.

1,195,796.

Specification of Letters Patent. Patented Aug. 22, 1916.

Application filed July 16, 1913. Serial No. 779,294.

To all whom it may concern:

Be it known that I, GIOVANNI EMANUELE ELIA, a subject of the King of Italy, and a resident of Rome, Italy, have invented a new and Improved Firing Apparatus for Submarine Mines, of which the following is a full, clear, and exact description.

This invention relates to a firing gear for submarine mines and relies for its operation upon the fact that a spherical or circular mine rotates by contact with the hull of a vessel.

The invention has for its general objects to provide an extremely simple firing apparatus which is thoroughly reliable and efficient in use, composed of comparatively few parts which are easily constructed and assembled and so designed that a high degree of safety is maintained in the launching or placing of the mine.

More specifically the invention has for its object to provide a novel arrangement and combination of parts whereby the rotary movement of the mine unfastens a coupling and allows the mine to rise under its own buoyancy and thereby operate the firing mechanism.

Another object of the invention is the provision of safety devices for preventing the separation of the parts of the coupling during the mooring of the mine or under the influence of the currents of the water in which the mine is planted.

An additional object is the employment of a simple, effective and novel firing mechanism arranged within the mine case and adapted to be actuated by the buoyancy of the mine when the coupling between the same and mooring cables is detached.

With such objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention, and wherein similar reference characters are employed to designate corresponding parts throughout the several views, Figure 1 is a

side view of a mine showing the resistance device thereof locked as in the act of mooring the mine; Fig. 2 is an enlarged sectional view of the firing mechanism locked against movement, as when the mine is being moored; Fig. 3 is a side elevation of the mine shown in the operation of being fired by contact with a ship; Figs. 4 and 5 are sectional views on lines 4—4 and 5—5, respectively, of Fig. 2; Fig. 6 is a view similar to Fig. 2 except that the firing pin is shown released and about to cause the explosion; Fig. 7 is an enlarged sectional view showing the clamping jaws for setting or cocking the firing pin as the released mine rises; Fig. 8 is a sectional view on the line 8—8, Fig. 7; and Fig. 9 is a detail view shown partly in section on the line 9—9, Fig. 2, and showing the locking means for the resistance rudder.

Referring to the drawings, A designates a spherical or circular mine which is provided at its bottom with a coupling device B, a resistance rudder C, a restraining means or lock D for the rudder, and an anchor cable E which is connected to the mine A through the locking device D and coupling B, there being in the mine A a firing mechanism F which is operated by the outward movement of the mine A under its own buoyancy when the coupling device B is uncoupled.

The coupling device B is made in three sections 1, 2 and 3, the section 1 being provided with a thread 4 at its upper end and this threaded end extends upwardly through an opening 5 in the bottom of the mine case 6 where a nut 7 screwed on the threaded end holds the upper section of the coupling in place. The lower end of the section 1 is provided with a threaded boss 8 which screws into an opening 9 in the intermediate section 2, such intermediate section having a threaded boss 10 which screws into a threaded opening 11 in the lower section 3. The threads on the boss 8 are of reverse pitch to the threads on the boss 10, for the purpose of causing the sections of the coupling to be detached by rotation of the mine in either direction. The lower section 3 is held against rotation with the mine case 6 to which the upper section 1 is fastened, because the anchor cable is of a character to

resist rotation with the mine, but additional means may be provided for this purpose if desired. This auxiliary means comprises an arm 12 fastened to the lower section 3 of the coupling and carrying a vertically disposed blade 13, such arm and blade constituting the resistance or rudder device C above referred to. When the sections of the coupling are unscrewed the mine A is free to rise because of its buoyancy, but connection is maintained with the anchor cable by a connecting rod 14 which has its upper end operatively connected with the firing mechanism within the mine while its lower portion passes through openings 15 and 16 in the sections 1 and 2 of the coupling device, and screws into the lower section 3 of the latter. Where this connecting rod passes out of the coupling device B and into the mine case there is a stuffing-box 17 which prevents the entrance of water and also a too sudden movement of the mine upwardly when the coupling device B is uncoupled.

In order to prevent the accidental or premature firing of the mine two safety devices are employed to prevent the unscrewing of the sections of the coupling. For this purpose one device comprises a readily breakable pin 18 that is normally fastened to studs 19 and 20 on the upper and lower sections of the coupling, such pin being of sufficient strength to prevent unscrewing of the parts of the coupling under the influence of the water currents on the mine or resistance device C, but when the mine is positively rotated by contact with a vessel the pin 18 readily breaks and allows the parts of the coupling to uncouple, as shown in Fig. 3. The other safety means is the locking device D, the same constituting a link between the anchor cable E and the lower section 3 of the coupling B. The device D is hingedly connected at 21 with the lower section 3 of the coupling device and the anchor cable E is connected with the opposite end, and on this free end 22 are upwardly-extending, spring bifurcations 23 which yieldingly engage a projection 23^a on the mine A and straddle the arm 12 of the resistance device C to prevent swinging of the latter during the operation of mooring the mine and while the mine anchor is unattached to the cable E. As soon as the anchor is attached to the cable and allowed to drop after the mine has been lowered into the water, the combined link and locking device D swings from the position shown in Figs. 1 and 2 to the position shown in Figs. 3 and 6, thereby releasing the resistance device C.

The firing mechanism F within the mine case 6 is preferably made in sections for convenience in manufacturing and assembling. This mechanism comprises a tube 24 divided into three sections *a*, *b* and *c*. The section *a* contains a preliminary charge of explosive

which is ignited by a detonator 25 mounted in a holder 26 which latter forms a coupling element which screws into a sleeve 27 in the upper end of the section *b*, such sleeve forming a guide for the hammer 28 of the firing pin 29. The upper end of the section *a* is closed by a plug 30, but when the charge is exploded by the detonator 25, the section *a* is destroyed and the shock explodes the main charge in the mine case 6. On the hammer 28 is a pin-like projection 31 which strikes and explodes the detonator 25. The lower end of the firing pin 29 passes through a guide 32 and terminates in the upper end of the lower section *c* of the tube of the firing mechanism, and surrounding the firing pin is a helical compression spring 33 which normally is untensioned but is adapted to be compressed during the upward movement of the mine when the same is released by the separation of the coupling device B. The lower guide 32 forms a coupling element which screws into a sleeve 34 in the upper end of the lower section *c*, and within this sleeve 34 is normally disposed a pair of clamping jaws 35 that are provided with lips 36 that engage with the squared head 37 on the lower end of the firing pin. These jaws are held together or in closed position against the tension of an opening spring 38 by means of the sleeve 34, and as soon as the jaws move out of the sleeve at the lower end of the latter they open and permit the firing pin to move upwardly to ignite the detonator 25. The jaws 35 are connected with the upper end of the connecting rod 14 by a coupling or lost motion device which comprises a socket member 39 to which the jaws 35 are hingedly connected at 40 and which has an opening 41 in its bottom to receive the upper end of the connecting rod 14, there being on the upper end of such rod a nut or head 42 which is larger than the opening 41, so that the member 39 will be connected with the rod 14.

When the parts are in normal position as shown in Fig. 2 the head 42 on the rod 14 is disposed above the bottom of the member 39, so that sufficient play is provided to permit the sections of the coupling B to unscrew when a ship comes into contact with the mine A. Of course before this unscrewing takes place the breakable element or pin 18 is first broken and finally the mine A is released and rises by its own buoyancy. During this upward movement of the mine the connecting rod 14, jaws 35 and firing pin 29 remain stationary, as these parts are connected together and also connected with the bottom section 3 of the coupling device B. During the upward movement of the mine casing the spring 33 is placed under compression as shown in Fig. 6, and finally the sleeve 34 passes upwardly beyond the jaws 35, so that the latter will open by the expansion of the spring 13^c

38, as shown in Fig. 6. The firing pin 29 being thus released moves upwardly by the expansion of the spring 33 and explodes the detonator 25, which in turn explodes the mine.

5 From the foregoing description taken in connection with the accompanying drawings, the advantages of the construction and method of operation will be readily understood by those skilled in the art to which the invention appertains, and while I have described the principle of operation, together with the apparatus which I now consider to be the best embodiment thereof, I desire to 10 have it understood that the apparatus shown is merely illustrative, and that such changes may be made when desired as are within the scope of the appended claims.

Having thus described my invention, I 20 claim as new and desire to secure by Letters Patent:

1. In a submarine mine, the combination of a charged buoyant body adapted to be rotated by contact with a vessel, a firing 25 mechanism therein, anchoring means, and a connecting device between the said anchoring means and body and provided with an organ securing its position, said connecting device having members secured respectively 30 to the mine body and the anchoring means, the said members being separable from each other for a predetermined extent, and operated by a continued rotation of the body to permit the said body to rise and operate 35 the firing mechanism.

2. In a submarine mine, the combination of a charged buoyant body, an anchoring means, a detachable coupling between the said means and body for permitting the 40 body to rotate by contact with the vessel and to have a limited upward movement with respect to the said means after rotating a certain amount, and a firing mechanism operated by the upward movement of the 45 said body.

3. In a submarine mine, the combination of a charged buoyant body, a firing mechanism therein, a detachable coupling on the said body and connected with the said 50 mechanism, and anchoring means connected with that portion of the coupling that is connected with the firing mechanism, said body being rotatable with respect to the anchoring means for opening the said coupling when the body is rotated by contact 55 with a vessel.

4. In a submarine mine, the combination of an anchoring means, a charged buoyant body, a coupling between the said means 60 and body and composed of a plurality of parts capable of detachment by rotation of the body in either direction, and a firing mechanism for the said body and actuated by the opening of the coupling.

65 5. In a submarine mine, the combination

of an anchoring means, a charged buoyant body, a coupling between the said means and body and composed of a plurality of parts capable of detachment by rotation of the body in either direction, a firing mechanism for the said body and actuated by the opening of the coupling, and a breakable device for preventing accidental opening of the coupling and breakable by the rotation of the body when in contact with a moving vessel.

6. In a submarine mine, the combination of an anchoring means, a charged buoyant body, a coupling having thread-connected sections connected respectively with the body 70 and means and adapted to be uncoupled by the rotation of the body through contact with a moving vessel, and a breakable device for preventing separation of the sections of the coupling except by rotation of 75 the said body.

7. In a submarine mine, the combination of an anchoring means, a charged buoyant body, a coupling having thread-connected sections connected respectively with the body 80 and means and adapted to be uncoupled by the rotation of the body through contact with a moving vessel, a device attached to that section of the coupling connected with the anchoring means for preventing rotation of such section, and a breakable device 85 for preventing separation of the sections of the coupling except by rotation of the said body.

8. In a submarine mine, the combination of an anchoring means, a charged buoyant body, a coupling having thread-connected sections connected respectively with the body 90 and means and adapted to be uncoupled by the rotation of the body through contact with a moving vessel, and a device attached to that section of the coupling connected with the anchoring means for preventing rotation of such section while the said body 95 rotates.

10. In a submarine mine, the combination of an anchoring means, a charged buoyant body, a coupling device having thread-connected sections and adapted to be uncoupled by rotation of the body through 105 contact with a moving vessel, means for holding one section of the coupling against rotation with the body, and a connection between the coupling section held by the said means and firing mechanism for actuating 110 the latter by the rising of the body when the sections of the coupling device are uncoupled.

9. In a submarine mine, the combination of a charged buoyant body, a firing mechanism therein, a coupling device having thread-connected sections and adapted to be uncoupled by rotation of the body through 115 contact with a moving vessel, means for holding one section of the coupling against rotation with the body, and a connection between the coupling section held by the said means and firing mechanism for actuating 120 the latter by the rising of the body when the sections of the coupling device are uncoupled.

10. In a submarine mine, the combination of a charged buoyant body, a firing mechanism therein, a coupling device having thread-connected sections and adapted to be uncoupled by rotation of the body through 125 contact with a moving vessel, means for holding one section of the coupling against 130

rotation with the body, a connection between the section that is held by the said means and firing mechanism for actuating the latter by the rising of the body when the sections of the coupling device are uncoupled, and a breakable device connected with the sections of the coupling for preventing uncoupling of the said sections except by rotation of the said body.

11. In a submarine mine, the combination of a charged buoyant body, a firing mechanism therein, an anchoring means, a coupling having detachably-connected parts united respectively with the body and anchoring means, a connection between the firing mechanism and that part of the coupling connected with the anchoring means for permitting the body to rise by buoyancy when the parts of the coupling are uncoupled to effect the firing of the mine, a resistance device connected with that part of the coupling that is attached to the anchoring means for holding such parts against rotation, and a locking device for holding the resistance device against rotation tending to uncouple the parts of the coupling.

12. In a submarine mine, the combination of a charged buoyant body, a firing mechanism therein, a coupling having detachably-connected parts, one of the parts being fixed on the body, a resistance device connected with the other part of the coupling for preventing turning thereof with the body, a connection between the firing mechanism and that part of the coupling connected with the said resistance device, a lock on the coupling for holding the resistance device against movement during the mooring of the mine, and an anchoring means connected with the lock and serving to release the same by the anchoring means exerting a downward pull on the mine.

13. In a submarine mine, the combination of a charged buoyant body, an anchoring means, a coupling between the said means and body, the parts of which are adapted to be separated to permit the body to have a limited upward movement after a predetermined number of revolutions in either direction by a contacting vessel, a firing mechanism within the body, a connecting element united with one of the parts of the coupling, said firing mechanism including a spring-actuated firing pin, and means between the said connecting element and firing pin for holding the latter under tension while the said body rises and finally releasing the said pin for effecting the explosion of the charge.

14. In a submarine mine, the combination of a charged buoyant body adapted to be rotated by contact with a vessel, an anchoring means, a preliminary charge of explosive, a firing pin for igniting the said preliminary charge, an element extending into the body, a coupling between the body and

anchoring means, the parts of which are adapted to be separated by a predetermined number of revolutions of the body in either direction, and to one of which parts the said element is attached, jaws on the said element normally engaging the said firing pin for holding the same stationary while the body rises, a spring arranged to be compressed by the rising of the body while the firing pin is held stationary, and means movable with the body for permitting the jaws to release the firing pin when the body has reached a predetermined point to cause the spring to actuate the firing pin.

15. In a submarine mine of the class described, the combination of a mine casing, a firing mechanism therein, an anchoring means, and a coupling between the said means and mine casing, the parts of which are adapted to be separated to permit the body to have a limited upward movement under its own buoyancy after the body has been rotated a predetermined number of times in either direction by contact with a vessel, said firing mechanism comprising a tubular structure, an explosive charge in the said structure, a firing pin for igniting the charge, a pair of jaws releasably engaged with the said firing pin, spring means tending to release the jaws from the firing pin, means movable with the said body for permitting the jaws to open and release the firing pin when the body has reached a predetermined position, a connection between the said jaws and one of the parts of the coupling to permit the said jaws to be released when the body rotates in either direction.

16. In a submarine mine, a charged buoyant body having firing mechanism therein, a coupling having one member secured to the body, means for operating the firing mechanism upon the separation of the parts of the coupling, a rudder carried by one member of the coupling, a locking device for said rudder and to which an anchoring cable is adapted to be secured.

17. In a submarine mine, a charged buoyant body having a firing mechanism therein, a coupling having one member secured to the body, means for operating the firing mechanism upon the separation of the parts of the coupling, a rudder secured to the lower member of the coupling, and a locking arm for the rudder to which an anchoring cable is adapted to be secured, said arm being pivoted to the lower coupling member and detachably engaging the said body.

18. In a submarine mine, a charged buoyant body having a firing mechanism therein, a coupling having one member secured to the body, means for operating the firing mechanism upon the separation of the parts of the coupling, a rudder secured to the lower member of the coupling, an angular

locking arm having one member pivoted to the lower member of the coupling and its other member detachably engaging the body, the member of the arm engaging the body being bifurcated to receive the arm of the rudder, and an anchoring cable attached to said locking arm.

In testimony whereof I have signed my name to this specification in the presence of two subscribing witnesses.
